UNITED STATES PATENT OFFICE.

HERMAN F. HOEHNE, OF KAUKAUNA, WISCONSIN.

THISTLE-PULLING MACHINE.

1,410,252.

Specification of Letters Patent. Patented Mar. 21, 1922.

Application filed March 27, 1919. Serial No. 285,575.

To all whom it may concern:

Be it known that I, HERMAN F. HOEHNE, citizen of the United States, residing at Kaukauna, in the county of Outagamie and 5 State of Wisconsin, have invented certain new and useful Improvements in Thistle-Pulling Machines; and I do declare the following to be a full, clear, and exact description of the invention, such as will enable 10 others skilled in the art to which it appertains to make and use the same.

My invention relates to improvements in thistle pulling machines of the general type disclosed by United States Patent No. 15 1,136,206 of April 20th, 1915. With machines of this character, considerable difficulty has been encountered by breakage of the springs which return the comb cleaners after actuation thereof, and the operating 20 means for the combs produce a very disagreeable noise. My invention, therefore, has for one object to overcome these difficulties by the provision of cams for moving the comb cleaners in both directions, so that the 25 springs will be eliminated and the device will operate practically without noise.

A further object is to provide in a single casting, a bearing for the transverse comb carrying shaft, a bracket for attaching such 30 bearing to the frame of the machine, and a cam arrangement for operating the comb cleaners.

Difficulty has also been experienced in retaining the cleaners in proper contact with 35 the combs, and a further object of my invention is to provide for effectively adjusting said cleaners to retain them in proper contact with the comb teeth.

With the foregoing in view, the invention 40 resides in the novel features of construction and unique association of parts hereinafter fully described and claimed, reference being made to the accompanying drawings which form a part of this application.

Figure 1 is a partial top plan view of 45 the machine embodying the improved features of construction.

Figure 2 is a longitudinal section on the plane indicated by the line 2—2 of Figure 1.

50 Figure 3 is an additional longitudinal sectional view on the plane indicated by the line 3—3 of Figure 1.

Figure 4 is a vertical transverse section on the plane of the line 4—4 of Figure 3.

55 Figure 5 is a perspective view of one of the castings above referred to.

Figure 6 is a perspective of the cover plate for the casting seen in Figure 5.

Figure 7 is a perspective view showing the manner of adjusting the comb cleaners. 60

In the drawings above briefly described, the numeral 1 designates the frame of a thistle pulling machine such as that disclosed in the patent above referred to, said frame being mounted upon a wheeled axle 2 65 which, by means of suitable driving connections 3, rotates a transverse shaft 4. This shaft carries a plurality of preferably cast, interchangeable spiders each having a suitable number of radial arms 5, the outer ends 70 of these arms carrying channel bars or the like 6 to which the thistle pulling combs 7 are secured. Cleaners 8 are provided for the combs 7 and each of these cleaners is by preference formed of an angle iron bar having 75 its flanges bent together at the ends of the bar to provide lugs 9 having openings through which the threaded outer ends 10, of substantially radial levers 11, project. Nuts 12 are threaded on the ends 10 in contact with the inner and outer sides of the lugs 9 and by adjusting said nuts, the cleaners 8 may be properly set with respect to the combs 7, for most effectively cleaning the latter. The levers 11 are fulcrumed between 80 their ends at 13 to projecting lugs 14 on the arms 5 and each arm is preferably provided with two of such lugs in order that the spiders carrying said arms may be interchangeably used at opposite sides of the machine. The inner ends of the levers 11 are provided with laterally extending shoes which are preferably in the form of rollers 15.

For rotatably mounting the shaft 4 and 90 providing cams for engagement with the rollers 15, for the purpose of operating the levers 11 to move the cleaners 8 along the teeth of the combs 7, I provide a pair of castings C which are identical in construction with the exception that one is adapted only for application to the left side of the machine, while the other is applicable to the right hand side thereof. The construction and arrangement of the castings C is shown 100 most clearly in Figures 3, 4 and 5. Each casting includes a substantially oval, vertical plate 16 having a bearing 17 formed integrally with one of its sides, and an attaching bracket 18 likewise formed integrally with said side, the bearing and bracket being also integrally joined to each 110

other. On its opposite side, the plate 16 is provided with a substantially ovate, eccentric hub 19 and with a continuous flange 20 spaced around said hub to provide a continuous channel 21 in which the rollers 15 travel. The bracket 18 is secured by bolts or the like 22 to the frame 1 and it will be seen that each casting forms a bearing for the shaft 4 as well as providing cam means 10 for operating the cleaners 8.

To prevent any possibility of the rollers 15 moving laterally from the channel 21 and also to assist in excluding dirt, weeds, etc., from said channel, a cover plate 23 is 15 provided for each casting C, said cover plate being spaced from the edge of the flange 20 a sufficient distance to accommodate the levers 11. This spacing is preferably accomplished by bosses 24 formed integrally with 20 the hub 19, and screws or the like 25 are passed through the plate 23 into said bosses to secure the former in place.

By providing the cam means afforded by the bosses 19 and the flanges 20, for operating levers 11, the arrangement commonly used may be eliminated with the result that no trouble is experienced from noise, spring breakage, etc. Furthermore, much better results are obtained when means such as the 25 lever ends 10 and the nuts 12 are provided for adjusting the cleaners 8 with respect to the combs 7. Since excellent results have been obtained in actual use of the machine, from the details herein disclosed, such details are preferably followed, but within the scope of the invention as claimed, considerable latitude is allowed for making numerous minor changes.

I claim—

40 1. In a thistle pulling machine, a wheeled frame, a pair of vertical plates each having a bearing on one side and an integral attaching bracket on such side, said brackets being secured to the sides of said frame, the 45 other side of each plate having an integral

eccentric hub and a continuous, integral flange around said hub, a transverse, driven shaft rotatably received in said bearings, radial arms carried by said shaft, combs on said arms, cleaners for said combs, levers 50 fulcrumed to said arms and carrying said cleaners, and laterally extending shoes on the inner ends of said levers received between said hubs and flanges.

2. A structure as specified in claim 1, together with plates for preventing lateral movement of the inner ends of said levers from said hubs and flanges, means for securing said plates to said hubs, and bosses spacing said plates and hubs apart to accommodate the levers.

3. A cast metal attachment for thistle pullers comprising a plate having a bearing integral with one of its sides and also having an attaching bracket integral with said side, the other side of said plate having an eccentric hub and a continuous flange around the same.

4. A structure as specified in claim 3; together with bosses on the ends of said hub, a second plate spaced outwardly from said flange by said bosses, and fasteners securing said second plate and bosses together.

5. In a thistle pulling machine, a wheeled frame, a transverse driven shaft mounted on said frame and having radiating arms provided at their outer ends with combs, cleaners for said combs, substantially radial levers fulcrumed between their ends to said arms and carrying said cleaners, said levers having threaded outer ends passing through the ends of said cleaners, adjusting nuts threaded on said lever ends and bearing against the inner and outer sides of said cleaners, and means for operating said levers to move said cleaners along said combs.

In testimony whereof I have hereunto set my hand.

HERMAN F. HOEHNE.
